UNITED STATES PATENT OFFICE.

MARY V. KAVANAGH, OF NEW YORK, N. Y., ASSIGNOR TO THE BUTTERICK PUBLISHING COMPANY, (LIMITED,) OF SAME PLACE.

DESIGN FOR A MISS'S COAT.

SPECIFICATION forming part of Design No. 18,165, dated March 6, 1888.

Application filed December 9, 1887. Serial No. 257,467. Term of patent 3½ years.

To all whom it may concern:

Be it known that I, MARY V. KAVANAGH, of the city, county, and State of New York, have invented and produced a new and original Design for a Pattern of a Miss's Coat; and I do hereby declare that the engraved prints accompanying this specification convey to any one accustomed to using paper patterns a clear understanding of how a garment made up by the 5 to pattern will appear.

The design shows long double-breasted fronts that exhibit a closing to some distance below the waist-line; a short close-fitting back shaping a point at the center of the lower edge; 15 a full gathered skirt depending from the lower

edge of the back; cape sections that describe a point at the front and back edges; a high arch between the points; revers turning over from their front edges and a dolman curve across the shoulders; a standing collar, and 20 coat-sleeves.

What I claim as my invention, and desire to secure by Letters Patent, is—

The design for a miss's coat, as shown in the engraved prints accompanying this specification. 25

MARY V. KAVANAGH.
